Primary Examiner — J. Thorn, Sr.(74) Attorney, Agent, or Firm — Benesch Friedlander Coplan & Aronoff LLP(57) CLAIM

The ornamental design for panels for slimming pants as shown and described.

DESCRIPTION

FIG. 1 is a front elevation view of first and second panels worn in the back of a slimming pants;

FIG. 2 is a back elevation view of the first and second panels worn in the back of the slimming pants;

FIG. 3 is a left elevation view of the first and second panels worn in the back of the slimming pants; and,

FIG. 4 is a right elevation view of the first and second panels worn in the back of the slimming pants.

The dashed and broken lines depicting stitching and the human form, shown in the drawings, are for environmental structure only and form no part of the claimed design. The shading indicates stretching of the material. The panels can be manufactured from cut and sew and/or seamless construction.
